(57) **CLAIM**

The ornamental design for a holster for small electronic devices, as shown and described.

DESCRIPTION

FIG. 1 is a front perspective view of one embodiment of the holster for small electronic devices invention;

FIG. 2 is a right side view thereof;

FIG. 3 is a bottom view thereof;

FIG. 4 is a top view thereof;

FIG. 5 is a left side view thereof;

FIG. 6 is a rear view thereof;

FIG. 7 is a rear view of a second embodiment, the same as the invention shown in FIG. 1, with a loop affixed thereto; and,

FIG. 8 is a top perspective view of the invention of FIG. 1, shown in use.

The broken line showing of a cell phone is included for the purpose of illustrating and forms no part of the claimed design.
